UNITED STATES PATENT OFFICE

2,027,062

PRESSING IRON

Julius Puretz, Brooklyn, N. Y.

Application December 23, 1933, Serial No. 703,728

1 Claim. (Cl. 68—26)

My invention relates to a new and improved pressing iron.

One of the objects of my invention is to improve a pressing iron of the type in which steam is admitted to the iron, and said steam is allowed to pass out through holes which are provided in the bottom or pressing face of the iron.

Another object of my invention is to improve an iron of this type in which a heater is provided, so as to heat the steam which is admitted from a boiler, which is external to the iron.

While the invention applies particularly to an iron which is connected to an external boiler, it also applies to an iron in which water in regulated quantities may be permitted to enter the iron, said water being vaporized within the iron by the heater.

Other objects of my invention are to provide suitable passages whereby the steam will be thoroughly heated by the heating element or device, before the steam passes out of the iron.

Other objects of my invention will be set forth in the following description and drawings which illustrate a preferred embodiment thereof, it being understood that the above general statement of the objects of my invention is intended merely to generally explain the same and not to limit it in any manner.

Fig. 1 is a perspective view.

Fig. 2 is a sectional view on the line 2—2 of Fig. 1.

Fig. 3 is a top plan view of the base of the iron.

Fig. 4 is a side elevation of Fig. 3.

Fig. 5 is a bottom plan view of the base of the iron.

Referring to Fig. 1, the iron generally includes a base 1 and a cover 2. The iron may include other conventional features such as a handle 3 and a valve 4 which is operated by a lever 5, in order to admit steam or water in regulated quantities, into the base of the iron.

The device also includes a heater H, which may be an electrical heater of any suitable type. This heater directly abuts the top of the base 1.

The base 1 may be made of any suitable metal or alloy, such as iron, steel, bronze or the like.

A metal plate 6 is superposed on the heater H and a rheostat R is located above the plate 6. The rheostat R is regulated by means of a turnable handle which is provided with a finger hold 7. The rheostat also includes the usual contact buttons 8.

The metal plate 6 extends substantially over the entire top of the base 1 and it serves to conduct the heat over the entire base 1. The

heater H can also extend over the entire top of the base 1.

Of course the heater H, in addition to the heating wires, includes sheets of mica or other insulation, in order to prevent any short circuit of the heating current.

As shown in Fig. 4, the base 1 is provided with a projection 1a, thus forming a shoulder 9, upon which the cover 2 rests. The steam or other fluid enters the base 1, through the inlet passage 10. The base 1 is provided with one or more passages in the top part thereof, and with one or more passages in the bottom part thereof.

In this particular embodiment, the inlet opening 10 communicates with a cylindrical passage 11 which is of smaller diameter than the inlet opening 10. The passage 11 communicates with lateral passages 12 and 14 which are at substantially the same level as the passage 11. The lateral passage 12 communicates with a longitudinal passage 15, and the lateral passage 14 communicates with a longitudinal passage 16. The passages 15 and 16 are also preferably cylindrical in cross section and they are at the same level with the passages 11, 12 and 14.

These passages can be formed by boring suitable openings in the base 1, and plugging the ends of these openings by means of suitable plugs P. These plugs P can be made of any suitable metal and they can be held in position by means of a drive fit, welding, cooperating screw threads or the like.

The longitudinal passages 15 and 16 communicate with lateral passages 17 and 18 at the rear or butt end of the iron and these passages 17 and 18 are also at the same level as the passages 11—16, inclusive.

The lateral passages 17 and 18 communicate with additional longitudinal passages 19 and 20 which are also located at the upper level previously mentioned.

The passages 19 and 20 respectively communicate with vertical bores 21 and 22 which communicate with longitudinal passages 23 and 24, which are provided at the lower level of the base.

The passages 23 and 24 communicate with inclined passages 25 and 26, which extend towards the tip of the base 1. The passages 23—26 inclusive are provided with openings 27, through which the steam passes to the fabric or garment which is being ironed. Screws or other fastening devices S clamp the cover against the base 1, and this clamping retains the members H and 6 and R in proper position. Supplemental fastening devices may be provided, but these are un-

necessary in view of the clamping grip which is produced by means of the members S. These members S pass through internal openings 28 in the base 1, so that the shanks of the members S clear the various passages which have been previously described.

When steam is admitted into the inlet opening 10, the steam traverses substantially the entire length of the base of the iron, said steam is then divided into two lateral streams or currents, these separate steam currents then move longitudinally substantially through the entire base, they again move laterally through the passages 17 and 18, and they then move longitudinally in the passages 19 and 20, through the maximum distance which is permitted by the tapered shape of the base of the iron.

While the steam or other fluid moves through the said upper passages in the base of the iron, the fluid is thoroughly heated by means of the heater H. The heat is also conducted by the plate 6 over the top face of the base 1.

The thoroughly heated steam, which is now dry and at a proper temperature, then passes to the lower passages 23-26.

Said lower passages 23-26 are preferably all in the same plane.

When I refer to the passages as bores, I do not wish to be limited to a construction in which the base is initially formed solid and in which the bores are subsequently formed, although this is the cheapest and most convenient way of forming such bores.

It will be noted that the bore 11 extends sub-

stantially from the butt end of the base to the point thereof and that it is substantially located at the median line of the base, so that the bore 11 has maximum length.

I have shown a preferred embodiment of my invention, but it is clear that numerous changes and omissions could be made without departing from its spirit.

I claim:

A base for a flatiron, said base being provided with an inlet bore 11 at its upper portion, and which extends substantially from the butt end of the base to the point thereof, and being located substantially at the median line of said base, said bore 11 communicating at its front end with transverse bores 12 and 14, said transverse bores 12 and 14 communicating with bores 15 and 16 which extend substantially to the butt end of the base, said bores 15 and 16 communicating with transverse bores 17 and 18 adjacent the butt end of the base, the bores 17 and 18 communicating with longitudinal bores 19 and 20 which terminate at substantially the transverse median line of the base, the bores 19 and 20 being connected by means of vertical bores 20 and 21, at substantially said transverse median line, with outlet bores which are located at the lower part of the base, said outlet bores being closed at their ends and having openings which communicate with the bottom face of the iron, the bores which precede the vertical bores 21 and 22 being all located at the upper part of the base.

JULIUS PURETZ.
